UNITED STATES PATENT OFFICE.

WALTER DANNENBERG, OF HUBBARD, IOWA.

HOG FEEDER.

Application filed October 28, 1926. Serial No. 144,749.

The present invention relates to a hog feeder and has for its prime object to provide a structure which will distribute into troughs arranged along the longitudinal sides of the device, means being provided in the troughs for regulating the flow of feed thereinto.

Another very important object of the invention lies in the provision of a device of this nature with troughs having therein means to prevent the hogs from scattering the feed therefrom.

A still further very important object of the invention lies in the provision of a device of this nature with a structure that is simple, strong, easy to adjust, thoroughly reliable and efficient in use, inexpensive to manufacture, and otherwise well adapted to the purpose for which it is designed.

With the above and numerous other objects in view as will appear as the description proceeds, the invention resides in certain novelties of construction, and in the combination and arrangement of parts as will be hereinafter more fully described and claimed.

In the drawing:

Figure 1 is a transverse vertical section taken through the device embodying the features of my invention,

Fig. 2 is a side elevation thereof.

Referring to the drawings in detail, it will be seen that the numeral 5 denotes a bottom which in the present instance may be rectangular in formation, but, of course, any other suitable shape may be provided. A board 6 lies on top of the bottom 5 and has its median longitudinal dimension coincident with the median longitudinal dimension of the bottom 5. End walls 7 rise from the bottom 5 and are provided with extensions 8. Side walls 9 are mounted between the end walls 7 being spaced inwardly from the side edges of said end walls 7. These side walls 9 are curved outwardly at their bottom edge. A top 10 is hinged as at 11 to one side wall 9. Roof sections 12 are suitably fixed to the side walls 9 a slight distance below their upper edges and rest on top of the upper edges of the extensions 8. A beam 14 extends between the end walls 7 and is triangular in cross section. This beam 14 is disposed immediately above the median longitudinal dimensions of the board 6 and bottom 5. A sheet metal member A is bent along its median longitudinal

dimension and said dimension rests along the upper apex of the beam 14 so as to form downwardly disposed sides 15 which diverge downwardly from each other to merge at 60 the sides of the board 6 into bottom portions 16 which terminate in upwardly and outwardly flanging portions 17 that have their extremities abutting cross walls 18 rising from the side edges of the bottom 5. It 65 is to be noted that the side walls 9 terminate at their bottom edges at the same level with the upper edges of the cross walls 18 and immediately above the juncture of the portions 16 and 17 of the sheet metal member. 70 This sheet metal member A forms a divider for distributing the feed evenly in the two side troughs located under the roof sections 12. Regulating gates 20 extend down into the trough and are hinged as at 21 to plates 75 22. The plates 22 are slotted as at 23 and bolts 24 mounted in the lower portions of the side walls 9 project through these slots 23 and have wing nuts 25 thereon so that the plates may be held in different adjusted 80 positions for regulating the distances at which the gates 20 will extend into the trough. On each portion 17 there are provided guard bales 26 which are of curved 85 formation and mounted in spaced parallel planes. These guards 26 prevent the hogs from rooting the feed from the troughs.

It is thought that the construction, utility, and advantages of this invention will now be clearly understood without a more detailed description thereof. The present embodiment of the invention has been disclosed in detail merely by way of example since in actual practice it attains the features of advantage enumerated as desirable 95 in the statement of the invention and in the above description. It will be apparent that changes in the details of construction, in the materials, and in the combination and arrangement of parts may be resorted 100 to without departing from the spirit or scope of the invention as hereinafter claimed or sacrificing any of its advantages.

Having thus described my invention what I claim as new is:

1. A device of the class described including, in combination, a bottom, a pair of end walls rising from the bottom, a pair of side walls extending between the end walls and terminating above the bottom, a pair of side walls rising from the longitudinal edges of the bottom and terminating at the same

level with the bottom edges of the side walls first mentioned, a beam extending between the end walls equidistant from the first mentioned side walls and above the bottom, a sheet metal member bent along its median longitudinal dimension and resting at said dimension on said beam to form downwardly and outwardly inclined side members merging into bottom members, said bottom members terminating in upwardly extending portions terminating in abutment with the second side walls.

2. A device of the class described including, in combination, a bottom, a pair of end walls rising from the bottom, a pair of side walls extending between the end walls and terminating above the bottom, a pair of side walls rising from the longitudinal edges of the bottom and terminating at the same level with the bottom edges of the side walls first mentioned, a beam extending between the end walls equidistant from the first mentioned side walls and above the bottom, a sheet metal member bent along its median longitudinal dimension and resting at said dimension on said beam to form downwardly and outwardly inclined side members merging into bottom members, said bottom members terminating in upwardly extending portions terminating in abutment with the second side walls, upwardly bowed members mounted on the terminal portions of the sheet metal member.

3. A device of the class described including in combination, a bottom, a pair of end walls rising from the bottom, a pair of side walls extending between the end walls and terminating above the bottom, a pair of side walls rising from the longitudinal edges of the bottom and terminating at the same level with the bottom edges of the side walls first mentioned, a beam extending between the end walls equidistant from the first mentioned side walls and above the bottom, a sheet metal member bent along its median longitudinal dimension and resting at said dimension on said beam to form downwardly and outwardly inclined side members merging into bottom members, said bottom members terminating in upwardly extending portions terminating in abutment with the second side walls, upwardly bowed members mounted on the terminal portions of the sheet metal member, said bowed members being disposed in parallel spaced relation.

4. A device of the class described including, in combination, a bottom, a pair of end walls rising from the bottom, a pair of side walls extending between the end walls and terminating above the bottom, a pair of side walls rising from the longitudinal edges of the bottom and terminating at the same level with the bottom edges of the side walls first mentioned, a beam extending be-

tween the end walls equidistant from the first mentioned side walls and above the bottom, a sheet metal member bent along its median longitudinal dimension and resting at said dimension on said beam to form downwardly and outwardly inclined side members merging into bottom members, said bottom members terminating in upwardly extending portions terminating in abutment with the second side walls, upwardly bowed members mounted on the terminal portions of the sheet metal member, said bowed members being disposed in parallel spaced relation, plates adjustably mounted on the lower portions of the first side walls, gates hingedly connected with said plates to swingably depend therefrom.

5. A device of the class described including, in combination, a bottom, a pair of end walls rising from the bottom, a pair of side walls extending between the end walls and terminating above the bottom, a pair of side walls rising from the longitudinal edges of the bottom and terminating at the same level with the bottom edges of the side walls first mentioned, a beam extending between the end walls equidistant from the first mentioned side walls and above the bottom, a sheet metal member bent along its median longitudinal dimension and resting at said dimension on said beam to form downwardly and outwardly inclined side members merging into bottom members, said bottom members terminating in upwardly extending portions terminating in abutment with the second side walls, upwardly bowed members mounted on the terminal portions of the sheet metal member.

6. A device of the class described including, in combination, a bottom, a pair of end walls rising from the bottom, a pair of side walls extending between the end walls and terminating above the bottom, a beam extending between the end walls equidistant from the side walls and a distance above the bottom, a sheet metal member bent along its median longitudinal dimension and resting at said dimension on said beam to form downwardly and outwardly inclined side members merging into bottom members, said bottom members terminating in upwardly extending portions terminating in abutment with the second side walls, upwardly bowed members mounted on the terminal portions of the sheet metal member, said bowed members being disposed in parallel spaced relation, plates adjustably mounted on the lower portions of the first side walls, gates hingedly connected with said plates to swingably depend therefrom, a cover hingedly mounted on one of the first side walls to extend over said first side wall, extensions on said end walls, and roof sections on said extensions.

7. A device of the class described including, in combination, a bottom, a pair of end walls rising from the bottom, a pair of side walls extending between the end walls and terminating above the bottom, a beam extending between the end walls equidistant from the side walls and a distance above the bottom, a sheet metal member bent along its median longitudinal dimension and resting at said dimension on said beam to form downwardly and outwardly inclined side members merging into bottom members, said bottom members terminating in upwardly extending portions and means for supporting the extremities of said upwardly extending portions a distance above the bottom.

In testimony whereof I affix my signature.
WALTER DANNENBERG.
